Attorney.

UNITED STATES PATENT OFFICE.

JOHN C. WELLER, OF CHICAGO, ILLINOIS, ASSIGNOR TO HARRY C. FARWELL, OF SAME PLACE.

WINDOW-SASH.

SPECIFICATION forming part of Letters Patent No. 681,009, dated August 20, 1901.

Application filed April 10, 1901. Serial No. 55,149. (No model.)

To all whom it may concern:

Be it known that I, JOHN C. WELLER, a citizen of the United States, residing at Chicago, in the county of Cook and State of Illinois, have invented certain new and useful Improvements in Window-Sashes; and I do hereby declare the following to be a full, clear, and exact description of the invention, such as will enable others skilled in the art to 10 which it appertains to make and use the same.

My invention relates to a novel construction in a window-sash of that kind known as "fireproof" construction, the object being to provide a sash made of sheet metal and 15 secure the glass in the same without the use of putty; and it consists in the features of construction and combinations of parts hereinafter fully described and claimed.

In the accompanying drawings, illustrating 20 my invention, Figure 1 is a partial outside elevation of a sash constructed in accordance with my invention. Fig. 2 is a partial inside elevation of same. Fig. 3 is a section, on an enlarged scale, taken on line 3 3 25 of Fig. 2. Fig. 4 is a partial section, on an enlarged scale, taken on line 4 4, Fig. 3.

In said drawings, A represents the sash, the rails B of which are built up of sheet metal and are rectangular in cross-section. Said 30 sash is provided with an inwardly-projecting flange C about midway of the depth of said rails, said flange being continuous around the four sides of the sash. To retain the glass D in said sash, four U-shaped members 35 E are provided, which when placed on the edges of the glass form an auxiliary frame for same and in this position are designed to fit within said sash and against the outer surface of said flange C. Said members E 40 are serrated on the edge F, which lies against said flange C, the portions G between said serrations forming lips which are adapted after the glass has been put in place to be bent over the inner edge of said flange C, and 45 thus firmly hold said members E and glass B in place. Said lips G may be embossed or otherwise artistically decorated to give a finished appearance to said sash. The outer portion of said members E are formed with 50 the outer edge turned back at an angle of

about thirty degrees, thus forming a V-shaped portion H, which is adapted to fill in the corner between the outer edge of the glass and the sash and when finished has the appearance of putty. The outer edge of said members E are again turned back inwardly upon themselves, thus forming a rounded edge I to come in contact with said sash and hiding the sharp edge J. The lips K of said U-shaped member E are formed closer together than 55 the base, thus causing said lips to fit closely to the glass with a slight spring-pressure, and consequently when same is in place to hold said glass firmly and nearly weatherproof.

I claim as my invention—

1. In a window, the combination with a sash provided with inwardly-extending flanges on its inner edges, of devices adapted each to receive one of the edges of the glass pane, each of said devices being provided with 70 flanges adapted to pass inwardly of the inner edges of said flanges of said sash and adapted to be bent over upon and engage said flanges to secure said glass pane in said sash.

2. In a window, the combination with a sash 75 provided with inwardly-extending flanges, of flexible strips adapted to receive the glass pane, and flanges on said strips adapted to be bent over upon and engage the flanges of said sash to secure said pane within said sash. 80

3. In a window, the combination with a sash provided with inwardly-extending flanges, of sheet-metal strips each having a flange on one edge bent over upon itself and bent to form an acute angle with the body of the 85 strip and provided on its other edge with a perpendicular flange the outer portion of which is cut to form lips at intervals, said strips being adapted to be slipped over the edges of the glass pane and said lips being 90 adapted to be bent over upon and engage the flanges of said sash to secure said pane within said sash, substantially as described.

In testimony whereof I affix my signature in presence of two witnesses.

JOHN C. WELLER.
